UNITED STATES PATENT OFFICE.

CURTIS D. PRUETT, OF DALLAS, AND WILLIAM KADERNASCHKA, OF TROUP, TEXAS.

RAILWAY CATTLE GUARD.

Application filed October 18, 1927. Serial No. 226,924.

This invention relates to railway cattle guards, and refers more particularly to such a device having for its objects as follows:

First, the prevention of access of livestock

5 to the rights of way of railways;

Second, to provide such a device which is so constructed that the railway roadbed at the point where the device is located may be maintained without disturbing in any way 10 or removing any part of the device.

Third, to provide a device which may be built on location from scrap material in combination with specially sawed ties.

Guards now in common use must be re-

15 moved to properly tamp ties on the roadbed. Also, those which have been most successful from point of maintenance heretofore, are of necessity, manufactured and shipped to the point of location, at an expense far in

20 excess of the expense attendant on the construction of this device. Therefore, the advantage of our device over others now in use is briefly: first, inexpensive construction, second, low cost of maintenance on location

25 where used, third, this device may be constructed and placed by the bridge or section gang regularly employed adjacent the said location, without additional skilled labor being necessary, fourth, this device has been 30 proven an absolute guard in preventing entrance of livestock to the right of way.

In the course of the following description taken in connection with the annexed drawings, these objects and advantages are 35 clearly elaborated on.

Figure 1 is a plan view of a pair of guards at the intersection of the railway and highway.

Figure 2 is a perspective view of one of the guard units.

40 Figure 3 is a cross section on lines 3—3 in Figure 2.

Continuing the description, in Figure 1, the rails 1—1 are shown passing over the 45 pair of guards with the highway 2 between them. The right of way fence 3—3 is shown, being continued across the railway by the guard device, the wings 4—4, such as are in common use, extend diagonally down- 50 ward from the fence to the device. A number of sawed nine foot track ties 5—5 each seven inches wide and nine inches deep are provided and have their ends spaced and braced by spacer member 6 bolted thereon 55 by screw bolts 7—7. On the ties between the rails and from the spacer member to the

60 rail are secured triangular strips 8—8 extending to a point on a level or slightly below the lower edge of the ball forming the top of the rail.

At spaced intervals between the ties, as shown in Figures 1, 2, and 3, are placed members 9—9, at an acute angle, in such a manner, that the parallel planes of the members, placed from the center of the roadbed 65 between the rails to one extremity of the tie assembly, is angularly disposed with relation to the parallel planes of the members on the opposite side of the roadbed.

Between and abutting against each adjacent pair of said members, hereafter called trip members are secured strips 10—10 to the ties. These brace and solidify the construction, hereafter are referred to as brace members.

70 In use, when livestock attempts to cross over the guard, the trip members cause them to slip and they will abandon the attempt. This device may be made of any suitable material, but should present on the upper or 75 exposed faces of the members a non-corrosive metal, to avoid excessive upkeep and to render it fire proof.

What we claim is:

1. In a railway livestock guard; in combination with a plurality of railway ties, of spacer members secured to the adjacent ends of the ties, of trip members angularly disposed between adjacent ties, and having braces therebetween, the trip members over 80 one half side of the road bed being in parallel planes, and those on the other half, being in parallel planes, the planes of the trip members on the first half being angularly disposed with respect to the planes of 85 those members over the second half of the roadbed, and a plurality of triangular strips in full clearance of the rails and covering the tops of said ties, the tops of said trip members and said triangular strips being upon 90 a plane one with the other.

2. A railway livestock guard, in combination with the rails and ties of a railway, comprised of a plurality of angularly disposed members secured between the said ties, 105 the said members on one side of the roadbed being in a parallel plane one with the other, the said members on the other side of the roadbed adapted to slope at an angle opposite to the angle of slope of the first group 110 of said members, triangular strips adapted to be secured to the tops of the ties, and

having their upper edges on a level with the tops of the angularly disposed members, and spaced members adapted to be secured to the adjacent ends of the ties.

5. 3. In a livestock guard for railways, a plurality of members diagonally disposed between a plurality of adjacent railway ties, half of said members being in parallel planes on one half of the roadbed, the other half 10 of said members being in a plane angularly disposed to the planes of the first half of the

members, the last half of the members being upon the second half of the roadbed, spacer members to bind and space the ties, and a triangular cover for each of the tie upper 15 surfaces, the tops of the tie covers and the diagonally disposed members being in one plane.

In testimony whereof, we have signed our names to this specification.

CURTIS D. PRUETT.
WILLIAM KADERNASCHKA.
